CLAIM

The ornamental design for a wall mount for exercise rack, as shown and described.

DESCRIPTION

FIG. 1 is a front, top, right perspective view of the wall mount for exercise rack showing our new design;

FIG. 2 is a front view thereof;

FIG. 3 is a left view thereof;

FIG. 4 is a right view thereof;

FIG. 5 is a top view thereof;

FIG. 6 is a front, top, right perspective view of the wall mount for exercise rack in an environment of use; and,

FIG. 7 is a front, top, right perspective view of the wall mount for exercise rack in an alternate configuration, in an environment of use.

The broken lines in the drawings illustrate portions of the wall mount for exercise rack that form no part of the claimed design. The additional broken lines in FIGS. 6 and 7 show environmental subject matter only and form no part of the claimed design.
